UNITED STATES PATENT OFFICE.

LE ROY M. BODINE, OF WALNUT, ILLINOIS.

DRAWER-PULL FASTENER.

1,319,948.

Specification of Letters Patent.

Patented Oct. 28, 1919.

Application filed August 8, 1919. Serial No. 316,176.

To all whom it may concern:

Be it known that I, LE ROY M. BODINE, a citizen of the United States, residing at Walnut, in the county of Bureau and State 5 of Illinois, have invented certain new and useful Improvements in Drawer-Pull Fasteners; and I do hereby declare the following to be a full, clear, and exact description of the invention, such as will enable others 10 skilled in the art to which it appertains to make and use the same.

The present invention relates to a drawer pull fastener, and aims to provide a novel 15 yet simple and inexpensive device to be applied to the interior of a drawer over the inner end of securing bolt or screw of the drawer pull, and serving to prevent the rotation of either the nut or bolt or screw head, to thereby prevent the drawer pull or knob 20 from loosening, as frequently is the case with the ordinary arrangement causing annoyance and inconvenience.

A further object is the provision of such 25 a device which will also serve as a protection to prevent fabrics and other articles placed within the drawer from being torn or injured by the exposed nut or head within the drawer as well as preventing the loss of the bolt or screw, or nut.

30 Another object is the provision of the device of the kind indicated which is adapted to hold either a nut against turning or a bolt or screw head having a slot for the engagement of a screw driver, to suit the device for different kinds of drawer pulls 35 with equal success.

With the foregoing and other objects in view, which will be apparent as the description proceeds, the invention resides in the 40 construction and arrangement of parts hereinafter described and claimed, it being understood that changes can be made within the scope of what is claimed without departing from the spirit of the invention.

45 The invention is illustrated in the accompanying drawing, wherein:

Figure 1 is a face view of the device.

Fig. 2 is a diametrical section of the device as applied to the inner side over a nut 50 and stem of the bolt or drawer pull or knob.

Fig. 3 is another diametrical section of the device showing it applied over the slotted head of a bolt or screw.

In carrying out the invention, there is

provided a cap or circular plate of metal or 55 other suitable material, having a convex boss 1 and a surrounding flat annular flange 2 provided with apertures 3 for the reception of screws 4 or other securing elements to fasten the cap to the inner side of the front 60 wall of the drawer, as seen in Fig. 2. The screw heads are preferably so countersunk as to be flush with the flange to avoid tearing fabrics which may brush past the cap, and the rounded or spherical surface of the boss 65 1 will serve as a protection to avoid the tearing of or injury to fabrics in being placed within or removed from the drawer. The cap has a square or other suitable polygonal socket or recess 5 entering the boss 70 from the flat side of the cap, to receive the nut 6 which is screw threaded onto the inner end of the drawer pull stem or bolt 7 that extends rearwardly through the front 75 wall of the drawer as usual. A numeral 8 designates an ordinary drawer pull or knob 80 which the bolt or stem 7 holds in place, it being apparent that the cap can be applied to the interior of the drawer at the inner end of the fastening means of the pull or 85 knob, to protect the same and also retain the nut 6 in place, to prevent the pull or knob from loosening. The socket 5 is con- 90 cayed at its bottom portion, so as to accommodate the projecting end of the bolt or stem 7. The device can be used in the drawers of dressers, buffets, and the like, to prevent garments and other fabrics from being torn or injured, as not infrequently happens, and to also retain the fastening means 95 of the pulls or knobs in place. The devices can be made in various styles and sizes for various drawer pulls and knobs.

In order that the device can be used for slotted heads of bolts or screws, a bar or 95 plate 9 is employed, the same being of a size to fit diagonally within the socket with its ends within diagonally opposite corners of the socket as seen in Fig. 1. Thus, as seen in Fig. 3, the bar or plate 9 can be inserted within the socket of the cap, so that one edge of said bar can extend within the slot of the head 6' of the screw or bolt 7', thereby holding said head in place against turning movement. This bar 9 is provided 100 within the cap to be used with slotted heads of screws or bolts that are inserted outwardly through the front wall of the drawer,

and if the device is to be applied over a nut, as seen in Fig. 2, bar 9 is removed.

If desired, the flange 2 can be cemented or glued in place, or can be fastened within 5 the drawer in any other suitable manner.

It is also preferable to provide the cap with a shallow circular depression or recess 10 surrounding the socket 5, to accommodate a washer that may be placed under the nut 15 or bolt head.

It will also be understood that the present device can be used on bolts and screws for other purposes for which it is suited.

Having thus described the invention, what 15 is claimed as new is:—

1. A drawer pull or similar fastener embodying a cap having a flat face and its opposite side convexed, said cap having an angular socket in its flat side to receive a 20 nut or a screw or bolt head, the cap having a shallow recess surrounding the socket and a flat annular flange surrounding said convexed portion and socket and flush with said

flat side for attachment to an object at several points surrounding said socket.

25

2. A drawer pull or similar fastener embodying a cap to be secured to the interior of a drawer and having a socket for receiving a nut or a bolt or screw head, and means within said socket for engaging a slotted 30 head.

3. A drawer pull or similar fastener comprising a cap having means for securing to the interior of a drawer, and having an angular nut-receiving socket, and a removable bar fitting in the socket with its ends within diagonally opposite corners of the socket, said bar being engageable with in a slotted bolt or screw head.

In testimony whereof I have signed my 40 name to this specification in the presence of two subscribing witnesses.

LE ROY M. BODINE.
